CLAIM

The ornamental design for a light string, as shown and described.

DESCRIPTION

FIG. 1 is a perspective view of a light string showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 1; and,

FIG. 12 is an enlarged view of portion 12 shown in FIG. 5. The light string is shown with symbolic breaks in its length, and the appearance of any portion of the light string between the break lines forms no part of the claimed design. The broken lines in the drawings depict portions of the light string that form no part of the claimed design. The broken lines of alternating length are for the purpose of illustrating the boundaries of the enlarged fragments shown in FIGS. 9-12 and form no part of the claimed design.
